US00D797786S

(12) **United States Design Patent** (10) **Patent No.:** **US D797,786 S**
Kim et al. (45) **Date of Patent:** **** Sep. 19, 2017**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Tae-eun Kim**, Seoul (KR); **Songmin Lee**, Seoul (KR); **Jiyun Lee**, Seongnam-si (KR)

(73) Assignee: **Samsung Electronics Co., Ltd.**, Suwon-si (KR)

(**) Term: **15 Years**

(21) Appl. No.: **29/574,746**

(22) Filed: **Aug. 18, 2016**

(30) **Foreign Application Priority Data**

Feb. 19, 2016 (KR) 30-2016-0007720

(51) **LOC (10) Cl.** **14-04**

(52) **U.S. Cl.**

USPC **D14/487**

(58) **Field of Classification Search**

USPC D14/485-495
 CPC .. G06F 3/0481; G06F 3/04817; G06F 3/0482;
 H04N 1/00408

(57) **CLAIM**

We claim the ornamental design for a display screen or portion thereof with graphical user interface, as shown and described.

DESCRIPTION

FIG. 1 is a front view of a first embodiment of a display screen or portion thereof with graphical user interface showing the new design; and,

FIG. 2 is a front view of a second embodiment thereof. The broken lines in the figures depict environmental subject matter and form no part of the claimed design. The outermost broken line in the figures shows a display screen or portion thereof and forms no part of the claimed design.

1 Claim, 2 Drawing Sheets
